His attorneys.

UNITED STATES PATENT OFFICE

GEORGE H. LOGAN, OF PITTSBURGH, PENNSYLVANIA

HEAD FOR MUSICAL INSTRUMENTS

Application filed February 23, 1929. Serial No. 341,900.

My invention relates to musical instruments and more particularly to heads or covers for musical instruments such as drums, both snare and bass, tom-toms, tambourines, banjos, tympana and the like.

In musical instruments having heads or covers made of layers of skin and which resound when struck a blow, either by direct application of force or by the vibration of 10 snare strings, difficulty is encountered when the skin becomes wet. A wet skin stretches unevenly so that there are areas under excessive tension and areas which are under a condition of slack so that the musical value 15 of the instrument is lost.

For instruments emitting a heavy sound or boom such as a bass drum, a head or cover comprising layers of fabric such as is shown in my Patent No. 1,018,767 granted February 20 27, 1912, may be utilized. As the tension applied to such cover is considerable, relatively thick layers of fabric must be utilized to withstand the strains imposed on the head.

When fabric layers are made sufficiently 25 thick to withstand the strains to which they are subjected, they are incapable of emitting the higher or sharp tones characterizing snare drums, banjos and the like.

I provide a head or cover for musical instruments emitting a sharp or high tone in which a layer of fabric and a layer of skin are united by a glue. The thickness of the fabric is sufficient to offer waterproofing protection to the layer of skin and at the same 35 time carry some of the tension applied to the cover. However, the major portion of the tension is withstood by the layer of skin. The presence of the layer of fabric which is uniformly secured to the layer of skin insures 40 that the skin will keep its shape when subjected to slight moistening, which moistening would be sufficient to render the skin unsuitable for emitting sounds if no fabric were present. The combined thickness of the skin 45 and fabric layer is sufficiently thin so that the head gives off the sharp tone characterizing a snare drum, banjos and the like, when struck sharp blows or when subjected to the vibration of strings such as snare strings and 50 the like.

While the head or cover is particularly useful in musical instruments emitting a sharp sound it may also be applied to musical instruments having a deeper tone, such as bass drums, tympana and the like.

55

The accompanying drawings illustrate certain present preferred embodiments of the invention in which

Figure 1 is a transverse sectional view of 60 a drum embodying my invention;

Figure 2 is a perspective view of a portion of a head or cover therefor;

Figure 3 is a similar view of a modified form of the invention; and

Figure 4 is a similar view of a further modified form of the invention. 65

Referring to Figures 1 and 2, a musical instrument 2 in the form of a snare drum comprises a body 3 of cylindrical form terminating in beads 4 at its edges, clamping rings 5 extending over the beads 4, and confining rims 6 on a head or cover 7. The heads 7 are placed at the opposite ends of the body 3 and are of similar construction. Lugs 8 are mounted on the clamping rings 5 and are provided with openings through which clamping bolts 9 extend. A turn buckle 10 is disposed between opposite pairs of bolts 9 for drawing the rings 5 inwardly of the drum. The inward movement of the rings 5 forces rims 6 of the heads 7 inwardly of the drum and tensions the fabric of the heads 7 around the edges of the beads 4, in a manner well known in the art. As the quality of sound of the instrument is controlled in large part by the tension on the heads 7, considerable pressure is applied to the rims 6.

70

75

80

85

One of the clamping rings 5 is provided with openings 11 through which snare strings 12 extend. The snare strings 12 are held in close engagement with the head 7 by a fixed bracket 14 and a movable bracket 15. The bracket 15 may be actuated by any one of a number of mechanisms which are well-known in the art and which constitute no part of the present invention. Upon the tightening of the bracket 15 the snare strings 11 are brought into tight engagement with the head 7 so that the vibrations of the snare 100

90

95

strings are imparted to the head for producing the desired sound from the drum.

Referring to Figure 2, the head 7 comprises a thin inner layer 16 of skin, and an outer thin layer of fabric 17. Calf skin is often used for such instruments and linen or silk are used as a fabric. The skin and fabric are united by a weatherproof bonding agent or by a glue. One form of glue which can be used for such purposes is described in my prior patent. It is to be understood, however, that other types of skins, fabrics and glues may be used in lieu of calf skin, linen or silk and the glue described in my prior patent within the spirit of the present invention as the foregoing specific materials are mentioned as examples and not as limitations of the invention. The fabric and skin are looped around the rim 6 and glued thereto. The complete head and rim are self supporting when removed from the drum body.

However, when pressure is applied to the rim 6, in order to draw the head over a drum bead 4, the head becomes very taut in order to develop the sharp sounds such as differentiate a snare drum or banjo from a deep boom of a bass drum or tympanum. However, it is to be understood that the head or cover of the present invention may be used on bass drums, tympana and the like.

When the head is stretched taut, the thin layer of skin withstands most of the tension. The layer of fabric serves as a waterproofing protector for the skin and also strengthens the head. At the same time the combined thickness of fabric and skin layers is not such as to interfere with the production of the desired sharp tones. Where layers of fabric alone are relied upon, the thickness of the fabric necessary to withstand the strains imposed upon the head are such as to render the instrument "dead", that is, the thickness of the layers of fabric is so great that they do not emit sharp tones, especially where the tones are produced by the vibrations of snare strings. The presence of the fabric permits the playing of the instrument in wet weather and even in rain without causing the skin to stretch or warp the drum.

Referring to Figure 3, in a modified form of the invention the head 7' is formed by placing the layer 16' of skin exterior to a layer 17' of fabric. This form of the invention is otherwise the same as the form illustrated in Figure 2. When the skin is placed externally of the fabric, the fabric keeps the skin in a serviceable condition even though it becomes somewhat moist.

Referring to Figure 4, a head 7" comprises a layer of skin 16" interposed between an inner layer 18 of fabric and an outer layer 19 of fabric. This form of the invention is particularly useful for heavier instruments such as bass drums and the like.

While I have shown and described certain

present preferred embodiments of the invention, it is to be understood that the invention may be otherwise embodied within the spirit of the invention and the scope of the appended claims.

I claim:

1. A head for a musical instrument comprising a layer of skin, a layer of fabric, and means for securing the skin and fabric to each other.

2. A head for a musical instrument comprising a thin layer of material, a thin layer of fabric and means for securing the material and fabric to each other.

3. A head for a snare drum comprising a layer of skin, a layer of fabric, and glue for securing the skin and fabric to each other.

4. A material for use as a vibratory diaphragm for musical instruments comprising a layer of skin, a layer of fabric and a bonding agent for securing the skin and fabric to each other.

5. A material for use as a head for a musical instrument emitting sharp tones comprising a thin layer of skin, a thin layer of fabric and bonding means for securing the skin and fabric to each other.

In testimony whereof I have hereunto set my hand.

GEORGE H. LOGAN. 95
